GLOW LAMP

Theodore Kowallis, Reading, Pa., assignor of
fifty per cent to Berkmont Company, a corpora-
tion of Delaware

Application October 19, 1932, Serial No. 638,469

4 Claims. (Cl. 176—122)

This invention relates to gaseous conduction lamps and more particularly to lamps of that character in which illumination is obtained by an electric discharge caused to pass from one to the other of two electrodes in a sealed enclosure containing a rarefied gas or vapor.

Among the principal objects of the present invention is to provide a gaseous conduction lamp, otherwise known as a glow discharge lamp, which is adapted for operation with either direct or alternating current at commonly available voltages.

The broad idea of providing electric glow discharge lamps for illuminating purposes is, of course, not new and various attempts have been made from time to time to provide a lamp in which the gas or vapor is rendered luminous by the discharge of current passing from one to the other of two electrodes sealed within the enclosure containing the gas or vapor.

One of the earliest forms of glow tubes was that known as the Geissler wherein a glow discharge was produced by the passage of an electric current through a gas of low pressure.

Experimenters have observed that in such types of glow tubes the surface of the negative electrode or cathode was surrounded by a very thin layer of luminosity; next to this very limited zone of luminosity was a dark space called

Crookes dark space. Immediately beyond this dark space was a luminous zone called the negative glow; and beyond this luminous zone was a second dark region, sometimes referred to as the Faraday dark space. Between this Faraday

dark space and the positive electrode or anode was the luminous region termed the positive column. It is among the principal objects of this invention to construct a gaseous conduction lamp wherein the negative and positive electrodes are so related in space and are so constructed that the non-luminous region known as the Crookes dark space is reduced to a substantially irreducible minimum in consequence of which the principal luminous discharge in the lamp is that which is obtained from the so-called negative glow.

Further objects of the invention are to provide a glow discharge lamp wherein the space relation and design of the positive and negative electrodes are such that it becomes possible to operate the lamp at relatively low voltages and by this is meant voltages which are comparable with those now in general use; to eliminate the necessity of interrupters, special inductive circuits and other devices for creating and maintaining the dis-

charge at such relatively low voltages; and to provide for a maximum luminosity when the electric current, either direct or alternating, is discharged between the electrodes of the lamp and through the gas sealed therein.

Still another object of the invention is to provide in a gaseous conduction lamp of the character described a plurality of sets of positive and negative electrodes uniformly spaced within the enclosure containing the sealed-in gas or vapor, these electrodes being relatively so related and mounted in position as to adapt the lamp for operation at low voltage and to eliminate all liability of injury to the electrodes should the lamp be subjected to shocks and excessive vibrations when in use, the arrangement of electrodes being further such as to render practically all of the surrounding gas or vapor luminous.

Other objects of the invention and advantages resulting from details and economies of construction thereof will be apparent more fully hereinafter.

The invention consists substantially in the combination, construction, arrangement and relative location of parts, all as will be described more fully hereinafter, as shown in the accompanying drawing, and as finally pointed out in the appended claims.

In the accompanying drawing:—

Figure 1 is an elevational view of the lamp constructed in accordance with the principles of the present invention;

Figure 2 is a vertical sectional view of the lamp taken on the line 2—2 of Figure 1;

Figures 3 and 4 are horizontal cross-sectional views taken respectively on the lines 3—3 and 4—4 of Figure 1;

Figure 5 is a perspective view of the lamp, a portion of the exterior bulb being broken away to more clearly show the internal construction thereof.

Referring now more particularly to the drawing, a lamp constructed in accordance with the present invention comprises an exterior bulb 10 of transparent glass, this exterior bulb being of any desired configuration but preferably of a configuration having a reduced neck 11 and an enlarged main body 12 the lower or outer end of which is drawn to a point and sealed, as at 13.

Disposed within the interior of the bulb 10 is a bulb 14 also constructed of glass and provided with an elongated, reduced neck 15, the lower end of the bulb 14 being sealed, as at 16. The upper ends of the concentrically arranged necks

11 and 15 are integrally united together, as at 17, preferably by fusing the glass together, thereby providing a unitary lamp assembly within which is provided an hermetically sealed chamber 18 adapted to be filled with a suitable gas or vapor of the helium or argon groups. Or the chamber 18 may be filled with a monatomic gas, such as neon, or any other gas or combination of gases which become luminous when an electric current is discharged therethrough, regardless whether the current is direct or alternating. The pressure of the gas contained within the chamber 18 may vary as desired and may range from 1 to 30 m. m. of mercury, the correct pressure of the gas contained within the chamber 18 being dependent upon the relative relation of the electrodes contained therein as well as upon the nature, shape, cross-sectional area, length, and number of the electrodes sealed within the gas-containing chamber 18.

10 The internal bulb 14, as employed in the lamp of the present invention, serves a triple function. In the first place, it serves as the supporting post for the several sets of electrodes to be presently described. In the second place, it serves the important function of controlling and regulating the volumetric capacity of the chamber 18. In the third place, it affords a very convenient means for providing in the center of the lamp a reflecting medium or surface for affording a more uniform dispersion or distribution of the light emanating from the lamp.

15 Referring again more particularly to the drawing, it will be observed that the inner bulb 14 is provided at opposite extremities of the bulbous portion thereof with a plurality of substantially radially extending anchors 19 of insulating material. Preferably, these anchors 19 are each formed of glass fused or otherwise integrally united to the bulb 14 constituting the support therefor. It will be observed that each of these anchors 19 comprises a radially extending section 20, a laterally turned section 21 and a longitudinally turned section 22. It will further be observed that the upper set of anchors 19 are so circumferentially spaced with respect to the lower set of anchors 19 that the longitudinally turned sections 22 of the upper set of anchors are respectively in vertical alignment with the outer extremities of the radially extending sections 20 of the lower set of anchors 19. Also, the upwardly turned sections 22 of the lower set of anchors 19 are respectively in vertical alignment with the outer extremities of the radially extending sections 20 of the upper set of anchors.

20 Extended downwardly through the center of the inner bulb 14 are a pair of conductor wires 23 and 24. Conductor wire 23 is extended to a point adjacent the lower end of the inner tube 14, as at 25, while conductor wire 24 is extended only to a point adjacent the lower end of the neck 15 of the inner bulb, as at 26. Secured to each of the upper set of anchors 19 are a pair of electric terminals 27a and 28a, while secured to each of the lower set of anchors 19 are a pair of electrode terminals 27b and 28b. The electrode terminals 27a and 28b are respectively anchored to the outer extremities of the radially extending sections 20 of the anchors 19, whereas the electrode terminals 28a and 27b are respectively anchored to the free extremities of the anchors 19. Each anchor thus constitutes a support for a pair of electrode terminals and in addition 25 serves to maintain each such pair of electrode

25 terminals in insulated and fixed relation. Interconnecting each set of vertically aligned electrode terminals 27a is an electrode 29, while interconnecting each set of vertically aligned electrode terminals 28a and 28b is an electrode 30. The electrodes 29 may constitute the positive electrode or anode, in which case the electrodes 30 constitute the negative electrodes or cathodes of the lamp. Suitably supported by the upper set of anchors 19 and electrically interconnecting each of the upper terminals 27a of the positive electrodes 29 is a wire 31 which in turn is connected to the conductor wire 24, it being observed that the wire 31 is insulated from the upper terminals 28a of the electrodes 30. Similarly, the lower set of anchors 19 support a wire 32 to which are electrically connected the electrode terminals 28b, this wire 32 being in turn connected to the conductor wire 23.

30 It will be observed that the electrodes 29 and 30 are arranged in sets circumferentially spaced about the inner bulb 14 and furthermore that the electrodes 29 and 30 of each such set are arranged in substantially parallel and fixed relation. Also, the radially extending sections 20 of the anchors are of such length as to position the electrodes 29 and 30 substantially equidistantly from the walls of the bulbs 10 and 14.

35 If desired, and demonstration has proved it to be desirable, the inner surface of the internal bulb 14 may be silvered or otherwise provided with a reflecting medium, to afford a more uniform and greater distribution of light from the lamp. A lamp thus constructed will be operated either on direct or alternating current. As a suitable material for the electrodes 29 and 30, tungsten has been found to be quite satisfactory. Also, it has been found that the lamp operates satisfactorily with the positive electrodes formed of nickel and the negative electrodes formed of molyb- 40 denum or platinum.

45 In order that a lamp as above described may be readily employed in direct current supply systems now in general use, it is preferable to provide the lamp with a screw plug base 33 to which the conductor wires 23 and 24 may be connected in the usual manner. In operation, when current of ordinary commercial voltage is supplied to the electrodes 29 and 30 through the conductor wires 23 and 24 and the electrode connecting wires 31 and 32, an electric discharge will be produced between each set of electrodes 29 and 30, the said discharge being coextensive in length with that of the electrodes and because of this extensive electric discharge substantially all of the gas contained in the lamp is rendered luminous.

50 It will be understood, of course, that the invention is susceptible of various changes and modifications which may be made from time to time without departing from the general principles or real spirit thereof and it is accordingly intended to claim the invention broadly, as well as specifically, as indicated by the appended claims.

55 What is claimed as new and useful is:—
1. In a gaseous conduction lamp, in combination, a pair of glass bulbs arranged one within the other to provide a sealed chamber between the walls thereof, the volumetric capacity of said chamber being regulated by the size of the inner glass bulb, a plurality of pairs of electrodes disposed within said chamber, each of said pairs of electrodes consisting of a positive and a negative electrode, and means extending radially from opposite ends of the inner bulb for supporting said pairs of electrodes in circumferentially spaced re-

- lation within said chamber and substantially equidistant from the axis of said inner bulb.
2. In a gaseous conduction lamp, in combination, a pair of glass bulbs arranged one within the other to provide a sealed chamber of predeterminedly fixed volumetric capacity, said chamber being adapted to be filled with an electrically conductive gas, a plurality of radially extending electrode anchors secured to the inner bulb adjacent opposite extremities thereof, each of said anchors extending well within said chamber, a pair of electrodes of opposite polarity supported by and extending between each set of vertically aligned anchors, the upper ends of all of the electrodes of one polarity being commonly connected to a conductor wire extending upwardly through the interior of the inner bulb and the lower ends of all of the electrodes of opposite polarity being similarly commonly connected to a conductor wire also leading upwardly through the interior of said inner bulb.
3. In a gaseous conduction lamp, in combination, a pair of bulbs arranged one within the other to provide a sealed chamber between the walls thereof of predeterminedly fixed volumetric capacity, said chamber being adapted to be filled with an electrically conductive gas, a plurality of sets of anodes and cathodes arranged within said chamber at circumferentially spaced intervals,
- and a plurality of insulating anchors carried by the inner bulb adjacent the upper and lower ends thereof for supporting said anodes and cathodes in fixed relation within said chamber, the upper anchors being respectively in vertical alignment with the lower anchors and each pair of vertically aligned upper and lower anchors being adapted to support, in insulated relation and substantially equidistantly from the axis of the inner bulb, a pair of said anodes and cathodes.
4. In a gaseous conduction lamp, in combination, an exterior bulb adapted to be filled with gas of relatively high electrical conductivity, an inner bulb arranged within said exterior bulb for reducing the gas content of the lamp, said bulbs being relatively so arranged as to provide a substantially elongated annular chamber predeterminedly fixed volumetric capacity within which said gas is sealed, and a plurality of sets of electrodes of opposite polarity arranged within said chamber at circumferentially spaced intervals, each set of positive and negative electrodes being arranged in parallel relation and substantially equidistantly from the axis of the inner bulb whereby to provide a gaseous discharge therebetween upon the application of a relatively low voltage thereto.
